Patented July 8, 1975

235,726

CANISTER VACUUM CLEANER OR SIMILAR ARTICLE

Clyde H. Williams, Coldwater, Mich., assignor to The
Scott & Fetzer Company, Bronson, Mich.

Filed May 28, 1974, Ser. No. 473,754

Term of patent 14 years

Int. Cl. D7—05

U.S. Cl. D7—168

Fig. 1

Fig. 4

Fig. 2

Fig. 3

Fig. 5

FIG. 1 is a perspective view of canister vacuum cleaner or similar article embodying my design.

FIG. 2 is a side elevational view.

FIG. 3 is an end elevational view showing the end opposite from that illustrated in FIG. 1.

FIG. 4 is a fragmentary sectional view showing additional details of the design taken on line IV—IV of FIG. 3.

FIG. 5 is a bottom plan view.

I claim:

The ornamental design for a canister vacuum cleaner or similar article, as shown.
